UNITED STATES PATENT OFFICE.

JAMES N. BAKER, OF BROOKLYN, NEW YORK, ASSIGNOR TO R. HOE AND CO., OF NEW YORK, N. Y., A CORPORATION OF NEW YORK.

ROUTING TOOL.

1,423,511.

Specification of Letters Patent. Patented July 25, 1922.

Application filed July 31, 1918. Serial No. 247,471.

To all whom it may concern:

Be it known that I, JAMES N. BAKER, a citizen of the United States, residing at 363 Lenox Rd., Brooklyn, county of Kings, 5 and State of New York, have invented certain new and useful Improvements in Routing Tools, fully described and represented in the following specification and the accompanying drawings, forming a part of 10 the same.

This invention relates to certain improvements in routing tools employed for routing or finishing electrotype, stereotype and other printing plates, and the invention relates 15 particularly to an improved holder for the cutting tools by which the routing is effected.

It is the especial object of the invention to provide a tool of simple construction 20 and design which may be driven by a high speed motor actuated by either alternating or direct current, and in which provision is made for controlling the motor speed to prevent the motor from running away when 25 there is no load on the tool, and in which provision is also made for cooling the motor, and for providing and directing an air blast or air current at the tool point so that the work is kept clear of chips, this being 30 especially desirable in routing tools where the tool is constantly moved from place to place on the work surface.

A further object of the invention is to provide a construction for effecting this 35 purpose, which is self contained, that is, in which all the operative parts are assembled to produce a unitary structure, which can be readily moved from place to place on the work, as required.

40 With these and other objects not specifically referred to in view, the invention will now be fully described in connection with the accompanying drawings, in which

Figure 1 is a vertical section of the improved routing tool holder.

Figure 2 is a plan view partly in-section showing the fan, the view being taken on line 2—2 of Figure 1.

Figure 3 is a side view partly broken away 50 of the cover or casing for the holder illustrating a method of supplying air to the holder; and

Figure 4 is a diagrammatic view on a reduced scale showing one method of mounting the holder with relation to the work. 55

Referring now to the drawings, the routing tool 1, which may be of any suitable character, is shown as clamped to a vertical tool shaft 2 by a rotary clamping device 3, of any usual or suitable character to enable the tool to be readily placed on or removed from the holder.

Devices embodying the invention in its preferred form, will include a holder in which the operating parts of the device are 60 carried so as to produce a compact unitary structure, and this holder will, furthermore, be designed so that a current of air may be directed through the holder for cooling the driving means, and so that a current of 65 air will be directed to the tool point so as to keep the work clear of chips. While the specific construction of this holder may vary somewhat, in the particular construction illustrated, there is provided a casing 4, preferably circular, which at its lower end has secured thereto a bottom 5, formed with a projection 6, in which is formed a bearing for one end of the driving shaft 2, before referred to. This driving shaft 2 extends 70 through the casing and takes its bearing at the other end in a bearing block 7, carried in a top plate 8, secured to the casing 4 in any suitable manner as by screws 9 taking 75 into a flange 10 formed on the upper end of 80 the casing.

The driving shaft 2 is driven by a high speed motor operated either by a direct or alternating current. The armature of this motor is secured to the driving shaft, and is indicated generally by the numeral 11, the field being indicated by the numeral 12. The top of the casing is enclosed by a perforated cap plate 13, this cap plate fitted 90 over the plate 8, before referred to, a space 95 14 being left between the cap plate 13 and the plate 8 for effecting ingress of air, as hereinafter referred to.

In accordance with the invention, means are provided for effecting the cooling of the 100 motor, and for directing a current of air to the point of the tool. In this class of machines, it is desirable also that controlling devices be provided for preventing the motor from running away when the tool is removed from the work, and the motor load ceases. In machines embodying the invention in its best form, a common means will be employed for effecting the cooling and controlling of the motor and for directing 105 110

an air current to the tool point. While the specific means may be varied, as illustrated there is provided a fan 15, which is secured to the driving shaft 2 and operating in a compartment formed between the bottom wall 5 of the casing and a plate 16, provided with a central aperture 17, through which the fan may draw air. This fan may be of any usual or suitable type, but in the particular construction illustrated, it comprises upper and lower supporting flanges 18, 19, between which are formed wings 20. The rotation of this fan acts to draw a current of air through the perforated cap 13 and space 14, before referred to, down through the casing around the motor armature, thus keeping the armature cool and the resistance offered by the fan, furthermore, acts to control the speed of the motor and keeps it from running away when the tool is removed from the work, and there is no load on the motor.

The fan 15, also, acts to produce a current of air, this air current being directed adjacent the working point of the tool so that it keeps the work free of chips about the tool point. While this may be effected in various ways, in the preferred construction, the casing 4 is provided with a port 21 which leads to a nozzle 22 secured to the wall of the casing, the delivery end of this nozzle being extended downwardly and inwardly so that the air current is delivered closely adjacent to the working end of the tool and obliquely to the tool, whereby the chips are effectively blown away from the tool point, and the operator is enabled to clearly see the work.

The tool may be handled by the operator in any desirable fashion, depending on the work employed. If desired, however, the tool may be mounted on the work support so that it can be readily removed to any part of the work desired. One such method of

mounting the tool is illustrated in Figure 4 of the drawings, in which there is provided an arm 23 pivoted at 24 to the work support 25. This arm 23 has pivotally secured thereto at 26 a tool carrying arm 27, to which the tool is clamped at 28, in any suitable manner, the tool being guided to the work by operating handle 29.

While the invention has been illustrated in what is considered its most practical form, it will be understood that within the scope of the claims various changes may be made in the specific construction and arrangement of the parts without departing from the invention.

What I claim is.

1. In a routing tool, the combination with a tool carrier, means for driving the carrier, a fan driven by the carrier, driving means for producing a current of air, and enclosed connections leading from the fan to the working end of the tool whereby an air current is directed to the tool point and the point kept free from chips.

2. In a routing tool, the combination of a casing, a motor mounted therein, a tool shaft taking bearings in the casing and driven from the motor, a perforated top for the casing, a fan located in the casing at the bottom thereof for producing an air current through the casing, and a nozzle leading from the fan to the tool point for directing the produced air current to the point of the tool.

3. In a routing tool, the combination of a casing, a motor mounted therein, a shaft driven from the motor taking bearings in the casing, a fan in the casing driven from the shaft, a nozzle leading from the fan to the tool point, and means for pivotally supporting the casing.

In testimony whereof, I have hereunto set my hand.

JAMES N. BAKER.
